WRITING INSTRUMENT

Charles K. Lovejoy, Atlanta, Ga., assignor to Scripto, Inc., a corporation of Georgia

Filed Aug. 5, 1960, Ser. No. 61,645

Term of patent 14 years

(Cl. D74—17)

FIG. 1 is a side elevational view of the writing instrument embodying my new design;

FIG. 2 is a front elevational view thereof as it appears with the writing point in projected position; and

FIG. 3 is a top plan view.

I claim:

The ornamental design for a writing instrument, as shown.
